UNITED STATES PATENT OFFICE.

ROBERT DANIEL TACKABERRY, OF LEWISTON, MAINE.

FLUID-PRESSURE REGULATOR.

1,213,972.

Specification of Letters Patent. Patented Jan. 30, 1917.

Application filed April 11, 1914. Serial No. 831,812.

To all whom it may concern:

Be it known that I, ROBERT D. TACKABERRY, a citizen of the United States, residing at Lewiston, county of Androscoggin, State of Maine, have invented certain new and useful Improvements in Fluid-Pressure Regulators, of which the following is a specification.

This invention relates to fluid pressure regulators and particularly to a reducing valve of the diaphragm and lever type.

The device of my present invention is especially adapted to the control of steam but may be used advantageously on water or gases. While in general designed to control reduced pressures between given limits, it is especially useful where a low pressure is desired or required, and where the initial pressure is liable to fall to or below the desired reduced pressure.

One of the objects of my present invention is to provide a reducing valve which will be positive and accurate in action and instantly responsive to the slightest variations in the pressure.

Another object in my invention is to provide a construction whereby the body of the valve may be turned to any angle and yet leave the diaphragm in a horizontal position, thereby permitting the valve to be attached to pipes running in any angle.

Another object of my invention is to provide for a direct transmission of power between the diaphragm and the valve stem by the use of one lever only.

A further object of my invention is to provide a construction whereby the lifting power of the diaphragm may be increased or decreased by adjusting the diaphragm along the lever.

Another object of my invention is to provide a connection for transmitting the movement of the diaphragm to the lever and in turn to the valve stem, which connection will give the desired lever effect without any lost motion.

These and other objects which will appear more fully hereinafter are attained by the use of the reducing valve described in the following specification. In the drawings forming a part of that specification, I have shown as illustrative embodiments two forms of valves, a double and a single seated valve, to which the principles of my invention are equally applicable.

In these drawings: Figure 1 is a plan view

of a device provided with a double seated valve in accordance with my invention with the valve shown in transverse section, Fig. 2 is a side elevation thereof with the valve and diaphragm shown in longitudinal section, Fig. 3 is a detail view of the rocking pivot which connects the diaphragm to the weighted lever, Fig. 4 is a view similar to Fig. 1 of a single seated valve in accordance with my invention, and Fig. 5 is a view similar to Fig. 2 of the valve shown in Fig. 4.

Referring first to the double seated valve shown in Figs. 1 and 2, I have indicated at 1 the body of a double seated valve. The valve 2 is adapted to be placed in a live steam main with its two valve heads vertically disposed so as to prevent scale and dirt from collecting at the seats. The inlet and outlet are designated by the letters A and B respectively. The course of the steam or other fluid entering through the inlet is indicated by the arrows. The steam flows around the valve 2 in opposite directions and at the same pressure. As shown in Fig. 2, however, the valve is closed. It is controlled by the movement of the diaphragm 3. The area of the valve is much less than that of the diaphragm and the diaphragm therefore has greater lifting power.

The valve may be adjusted by a coil spring 4 which contacts with a stud 2¹ on one of the valve heads and is intended to prevent the valve from fluttering on its seats. Tension on the spring 4 is increased or decreased by means of the adjusting screw 6 which is threaded into a boss 7 on the valve body.

The valve body has a projecting hub 8 to which is clamped a bracket 9 from which the diaphragm casing is hung. The bracket 9 permits the valve body to be swung in any angle while leaving the diaphragm in a horizontal position as shown in Fig. 2. The importance of this is that it permits the valve to be attached to pipes running in any angle.

The numeral 10 indicates a stuffing box set on the valve stem 5 beyond the bracket. The stuffing box is always in a horizontal position and is always away from the condensation.

The movements of the diaphragm are transmitted to the valve stem 5 by a right angled lever 11. The upright arm of this lever is connected to the valve stem in any suitable manner. As a convenient form, I have shown in these drawings a bifurcated

link 12. The valve stem is received in one end of the link and the lever 11 fits in the slot of the other end and has slight play therein by means of the slots 12^a and the bolts 12^a. This form of connection however may obviously be varied, and in Fig. 5, I have shown a ball and socket joint 29 instead of a link connection.

The lever 11 is pivoted to the bracket 9 by a pin 13 journaled in a pair of ears 14 on the bracket. The lever connects the valve stem directly with the diaphragm so that the valve will respond to the lift of the diaphragm under the slightest variation in the steam pressure. The single lever secures a direct transmission of power which is effective to close the valve against practically any pressure carried on the steam main under a relatively slight pressure acting on the diaphragm.

Since the movements of the diaphragm effects the regulation of the valve it is important that it should be capable of positive control so as to regulate its effective lift. The diaphragm is therefore made adjustable along the lever so that its effective lifting power may be increased or decreased at will. In order that the diaphragm casing may move relative to the bracket 9 from which it is hung, I provide a sliding joint connection between the diaphragm casing and the bracket. The sliding joint consists of a plate 15 adjustable in guide lugs 15¹ on the upper face of the diaphragm case 16. The plate has two elongated slots 17 in which work two adjusting screws 18 which may be tightened to fasten the diaphragm casing in adjusted position.

The adjustment of the diaphragm along the lever is through a rocking pivot 19 and a plurality of holes 21 in the lever. The pivot transmits all movements of the diaphragm without any lost motion to the lever and with the sliding joint permits adjustment of the diaphragm along the lever. The lower end of the pivot 19 seats and finds bearing in a bushing 20, seating on the diaphragm and projecting through the diaphragm case 16. This end of the pivot is slightly smaller than the bore of the bushing, thereby eliminating friction while permitting the desired movement. The upper end of the pivot is forked to embrace the lever on two sides (see Fig. 3). It is bolted to the lever by a bolt which may be set up selectively in any of the series of holes 21 in the lever. These holes with the sliding joint on the casing 16 therefore permits the diaphragm to be adjusted relative to the valve to vary the effective lift of the diaphragm.

The diaphragm is usually a rubber disk clamped between the two edges of the diaphragm case by the screws 3¹. The diaphragm is protected by an overlying protective device composed of two sets of flexi-

bly connected members extended radially from the base of the bushing 20. The base of the bushing 20 is formed as a solid piece of metal having an annular recess extending circumferentially thereabout. Pinned loosely in this recess so as to be capable of a slight vertical play is a series of radially extending substantially contiguous members 35. The members 35 are preferably somewhat arrow shaped in plan (see Fig. 1), and are arranged with their heads pinned in the recess and their shanks extending outwardly toward the outer circumference of the diaphragm case. Loosely connected with said members is a series of radially extending substantially contiguous members 36. The members 36 are preferably somewhat sector shaped in plan as seen in Fig. 1 and have their curved edges disposed toward the outer circumference of the diaphragm case so as to rest on an internal circumferential ledge 22 formed on one of the sections of the case. The loose connection between each member 35 and 36 is conveniently effected by slotting each member 36 transversely as indicated at 37 (Fig. 2) and pressing up the metal from the forward edge of each slot to the inner transverse edge of the plate to form a yoke like saddle member 38 raised above the plane of the rest of the plate and preferably of a length but slightly greater than the width of the shank of the member 35. The outer or shank end of the arrow like members 35 are adapted to be inserted through the openings thus formed under the yokes 38 until the inner edges of the members 36 stop against the shoulders formed by the heads of the members 35. In this position the shanks of the members 35 partially overlie the plates 36 with the yoke like members 38 bearing on the upper sides of the shanks. The members 35 and 36 when thus assembled form a flexible disk like protector substantially overlying the rubber diaphragm disk 3. The protector thus formed will not interfere with the movements of the diaphragm disk 3 responsive to variations in the pressure, and yet completely protects the diaphragm by compelling it to form the same arc on every upward movement, thus preventing the diaphragm from bulging in places and hence increasing the life of the rubber diaphragm disk.

The point for which the reduced pressure is set may be varied. This point is governed by the number of weights 23 hung on the rod 24 which is attached to the free end of the lever 11. The upper end of the rod 24 is forked and the lever has a plurality of holes 25 in any of which a bolt may be selectively set up to position the rod 24 at a desired point along the lever.

A pipe 26 leads from the bottom of the diaphragm case to the drying cylinder, ket-

tle or other place where the reduced pressure is required.

The diaphragm is subjected to pressure from the delivery conduit through the pipe 26. These connections have not been shown in the drawings but the word "pressure" and the representation of an arrow appear thereon to indicate that the pressure enters pipe 26.

The operation of this form of valve is as follows: The valve 2 is normally open and is only closed when the reduced pressure reaches the point for which it is set. The steam or other fluid entering through the inlet is distributed in opposite directions (as indicated by the arrow in Fig 2), and with the same pressure through the valve body. When the initial pressure falls below a certain limit (governed by the weights 23) or when a low reduced pressure is desired, steam enters the pipe 26 from the drying cylinder or other place. This lifts the diaphragm which through its rocking pivot 19 rocks the lever 11 on its pivot 13. The rocking motion of the lever is transmitted to the valve stem 5 by the connection 12 thereby closing the valve and effecting a reduction in the pressure. When the reduced pressure reaches the point for which it is set the valve is again adjusted and is so maintained by the diaphragm. This low pressure point may be varied either by varying the number of weights 23 or by moving the rod 24 along the lever. If desired the weights 23 could be dispensed with and a heavier spring be used in the place of the coil spring 4 to accomplish the same purpose.

The effective lifting power of the diaphragm may be varied by adjusting it along the lever. The sliding joint and selective engagement of the pivot member 19 in the holes 21 permit this adjusting movement.

The single lever 11 not only secures a direct transmission of power effective to close the valve against practically any pressure carried on the steam main under a relatively slight pressure acting on the diaphragm but makes the device highly responsive to even the slightest variation in the steam pressure.

Referring now to Fig. 4 in which I have shown a single seated valve: The valve body has a piston shaped valve 27 which fits closely into a cylinder 28. The piston 27 is much larger than the valve opening so that when pressure is obtained on the low pressure side it will pass through the ports 27¹ and flow behind the piston. This creates a counter pressure behind the piston and assists the diaphragm to regulate the valve at the desired pressure. The pressure required is governed by the weights 23. The parts are otherwise the same as in Fig. 1 except that a ball and socket joint 29 is

used in place of the link connection 12 of Fig. 1, and that the piston is grooved at 30 to provide a water packing.

Various other modifications in the form and construction of my device may obviously be resorted to within the limits of the appended claims.

What I therefore claim and desire to secure by Letters Patent is:

1. In a fluid pressure regulator, in combination, a valve body, a valve therein, a diaphragm case, a diaphragm therein, a hanger connecting said diaphragm case and valve body and permitting angular adjustment of said body relative to said case, a valve stem, operative connection between said diaphragm and stem, and means including a sliding joint between said diaphragm case and hanger for permitting adjustment of said case relative to said valve effective to vary the lift of said diaphragm. 75

2. In a fluid pressure regulator, in combination, a valve body, a valve therein, a diaphragm case, a diaphragm therein, a hanger connecting said case and body and permitting angular adjustment of said body relative to said diaphragm, said hanger having a sliding connection with said case permitting adjustment of said case relative to the valve, and a valve stem, a weighted lever 90 fulcrumed on said hanger and connected with said stem, and a rocking connection between said diaphragm and lever for transmitting the effective motions of said diaphragm to said lever said rocking connection having 95 selective engagement with the lever whereby the diaphragm may be adjusted along the lever to vary its effective lift. 100

3. In a fluid pressure regulator, in combination a reducing valve, a diaphragm operatively connected therewith and disposed to control the effective constant position of said valve, and a flexible protector for said diaphragm comprising a plurality of series of members overlying said diaphragm, each member of one series loosely connected with the adjacent member of an adjacent series. 105

4. In a fluid pressure regulator, in combination a reducing valve, a valve stem, a lever connected with said stem, a diaphragm, an anchoring member mounted on said diaphragm, a connection between said member and said lever, and a flexible protector for said diaphragm comprising a plurality of series of members having a loose 110 connection with said anchoring member and one series loosely connected with an adjacent series. 115

5. In a fluid pressure regulator in combination, a reducing valve, a valve stem, a lever connected with said stem, a diaphragm, an anchoring member mounted on said diaphragm, a connection between said member and said lever, and a flexible protector for said diaphragm comprising a plu- 120 125 130

- rality of series of radially disposed protector plates having loose connection with said anchoring member and one series detachably connected with an adjacent series.
- 5 6. A protector for a diaphragm disk comprising a flexible disk made up of a plurality of flexibly connected series of protector members.
- 10 7. A protector for a diaphragm disk comprising a flexible overlying disk made up of a plurality of radially extending flexibly connected series of protector plates.
- 15 8. A protector for a diaphragm disk comprising a flexible overlying disk made up of two sets of radially extending flexibly connected protector plates, one set of plates having a general arrow like form and the other set of plates having a general sector shape, the shanks of said first named set overlapping and loosely connected with said second named set.
- 20 9. In combination with a diaphragm and an anchoring member associated therewith, a protector for said diaphragm comprising a plurality of series of protector members, each member of one series loosely connected with the adjacent member of another series and the members of one series having a loose connection with said anchoring member.
- 25 10. In combination with a diaphragm and an anchoring member associated therewith, said member having a circumferential recess, a protector for said diaphragm comprising two series of radially extending protector members, the members of one series loosely secured in said recess of the anchoring member and the members of the other series supported on said diaphragm and loosely connected with the adjacent members of the first named series.
- 30 11. In combination with a diaphragm, and an anchoring member associated therewith, said member having a circumferential recess, a protector for said diaphragm comprising sets of radially extending protector plates, the members of the inner set being loosely pinned in said recess of the anchoring member and flexibly connected with the members of the outer set, each of the plates in the outer set being slotted and having the metal adjacent one edge of the slot pressed out to provide an opening in which the end of the coöperating protector plate is receivable to provide a flexible connection for the sets of plates.
- 35 12. A protector for a diaphragm consisting of two series of members arranged in overlying relation to the diaphragm, one series loosely connected with the other.
- 40 13. A protector for a diaphragm consisting of two overlapping series of members arranged in overlying relation to the diaphragm.
- 45 14. A protector for a diaphragm consist-
- ing of two series of members arranged in overlying relation to the diaphragm, one series having openings to receive the adjacent portions of the other series.
- 50 15. A protector for a diaphragm consisting of two series of members arranged in overlying relation to the diaphragm, one series overlapping the other and having a connection therewith permitting a limited movement in the direction of movement of the diaphragm.
- 55 16. In combination, a rotatable valve body, a valve therein, a diaphragm case longitudinally adjustable relative to said body, a diaphragm therein, an operative connection between said valve and diaphragm, and a support having a connection at one end disposed for engagement with said valve body and permitting rotation thereof relative to said case and having a connection at its other end with said case permitting longitudinal adjustment of the case relative to the valve body.
- 60 17. In combination, a rotatable valve body, a valve therein, a diaphragm case longitudinally adjustable relative to said body, a diaphragm therein, an operative connection between said valve and diaphragm, and a support having a clamping collar at one end disposed for engagement with said valve body and permitting rotation thereof relative to said case and having a sliding connection at its other end with said case permitting longitudinal adjustment of the case relative to the valve body.
- 65 18. In combination, a valve body, a valve therein, a diaphragm case, a diaphragm therein, an operative connection between said valve and diaphragm and a hanger having a connection with said body and case at opposite ends and disposed to position said case below the plane of and at substantially right angles to said body.
- 70 19. In a fluid pressure regulator, in combination, a vertically disposed valve body, a valve therein, a horizontally disposed diaphragm case, a diaphragm therein, an operative connection between said valve and diaphragm and a hanger for said case having a collar at one end disposed to clamp said valve body and permitting adjustment thereof about its axis without disturbing the horizontality of said case.
- 75 20. In a fluid pressure regulator, in combination, a valve body, a valve therein, a horizontally disposed diaphragm case, a diaphragm therein, and a hanger for said case having a clamping connection with said valve body permitting adjustment thereof about its axis without disturbing the horizontality of said case, and said hanger having a connection with said case permitting bodily adjustment thereof toward and from said valve body.
- 80 21. In combination, a vertically disposed

5 rotatable valve body, a valve therein, a horizontally disposed diaphragm case, a diaphragm therein, an operative connection between said valve and diaphragm, and a support for said case having a connection with said valve body permitting rotation of said body about its axis without disturbing the horizontality of said case.

10 22. In combination, a valve body, a valve therein, a diaphragm case, a diaphragm therein, an operative connection between said valve and diaphragm, a support having connection with said body and case at opposite ends and disposed to position said case below the plane of and at substantially right angles to said body, and a protector overlying said diaphragm to prevent rupture of the diaphragm.

15 23. In combination, a valve body, a valve therein, a diaphragm case, a diaphragm therein, an operative connection between said valve and diaphragm, a support having connection with said body and case at opposite ends and permitting angular adjustment of said valve body relative to said case, and an overlying protector for said diaphragm to define the arcual movement of the diaphragm and thus prevent rupture of the diaphragm.

20 24. In combination, a vertically disposed rotatable valve body, a valve therein, a horizontally disposed diaphragm case, a diaphragm therein, an operative connection between said valve and diaphragm, a support for said case having a connection with said valve body permitting rotation of said body

about its axis without disturbing the horizontality of said case, and a protector for said diaphragm acting in opposition to the pressure to prevent rupture of the diaphragm.

25 25. In combination, a diaphragm case and a valve body arranged with their axes at an angle to each other, a diaphragm in said case, and a valve in said body operatively connected with each other, and a connection between the case and body permitting their relative angular adjustment.

30 26. In combination, a diaphragm case and a valve body arranged with their axes at an angle to each other, a diaphragm in said case and a valve in said body operatively connected with each other, and a connection between the case and body permitting their relative angular adjustment and also permitting relative longitudinal adjustment toward and away from each other.

35 27. In combination, a diaphragm case and a valve body arranged with their axes at an angle to each other, a diaphragm in said case, and a valve in said body operatively connected with each other, and a connection between the case and body permitting relative angular adjustment of the one without disturbing the setting of the other.

40 60 In testimony whereof I affix my signature in presence of two witnesses.

65 ROBERT DANIEL TACKABERRY.
